UNITED STATES PATENT OFFICE.

WILLARD T. FARRAR, OF CONCORD, MASSACHUSETTS.

ADJUSTABLE LADDER-HOOK.

Specification of Letters Patent No. 31,963, dated April 9, 1861.

To all whom it may concern:

Be it known that I, WILLARD T. FARRAR, of Concord, in the county of Middlesex and State of Massachusetts, have invented an 5 Improved Adjustable Ladder-Hook, of which the following is a full, clear, and exact description, reference being had to the accompanying drawings, making part of this specification, in which—

10 Figure 1, represents a ladder with my improved adjustable hook attached thereto, and the ladder placed on the roof of a building showing an application of my invention. Fig. 2, a view of the hook detached. Fig. 3, shows a modification of my invention.

I am aware that ladders have been furnished with hooks, permanently attached to their sides at the upper end, and that these 20 have long been in use by firemen, builders, painters and others whose occupations required them to mount the roofs of houses, the hooks being used to secure the ladder from falling, either by placing the hooks 25 over the gutter or eaves when ascending from the ground or over the ridge (as shown in Fig. 1) when at work on the roof. All ladders however are not supplied with these hooks, as they would be inconvenient 30 in many instances; yet they are very often wanted, particularly in such an emergency as a fire, or where workmen are compelled to carry their own ladders from a distance to the place where they work, because a 35 ladder with hooks is needed.

The object of my present invention is to obviate this difficulty, and to furnish a hook which may be easily transported separate 40 from the ladder, and may be applied to any ordinary ladder when required; and my invention consists, in a hook to be attached to the ladder by clamping it to the two upper rounds, the clamp being made adjustable so that it may be fitted to ladders of 45 different sizes, or in which the rounds are at different distances apart.

That others skilled in the art may understand and use my invention I will proceed to describe the manner in which I have carried out the same.

In the said drawings A is the ladder, B, the hook, which has its shank formed square at a and has a screw b , cut on its end. A

clamp C has a hooked portion d made to fit over one of the rounds of the ladder, and two lugs e , f , the former of which has a square hole through which the square part of the shank a slides, while the other lug f has in it a round hole through which the screw b passes and in which it slides freely. 55 A thumb nut g on the screw b , serves to force the clamp C farther up on the shank toward the hook. A stationary clamp D is formed on the hook B, immediately below its bend. This hook is applied to the ladder in the following manner: The clamp D is placed against the top round of the ladder, and the hook d of the clamp C under the second round against which it is pressed, 60 and the nut g is turned up to bind it securely 65 against the round. The length of the screw b allows considerable motion to the clamp C to accommodate the variation of distance between the rounds of different ladders. If required two of these hooks may be applied 70 to a ladder, one on each side, but in practice I have found that in most situations, particularly when on the roof that one is preferable, as the ladder can be more easily managed, that is moved about. 75

Other mechanical arrangements of the two clamps may be used without departing from the spirit of my invention, for example in Fig. 3, I have shown a modification of my invention, in which the hook B^2 is 80 bent over at its lower end at f^2 to catch over the second round, its shank is flattened out at a^2 to give room for a slot b^2 through which passes the screw rod c^2 of the adjustable clamp C^2 . This clamp is bent up at e^2 85 to embrace the upper round, and after being adjusted to it, so as to hold the clamp f^2 up against the round with which it is in contact, is drawn up and is secured by a thumb nut D^2 . 90

What I claim as my invention and desire to secure by Letters Patent is—

A removable ladder hook, to be clamped to a ladder when required, one of its clamps being made adjustable, substantially as 100 specified.

WILLARD T. FARRAR.
